UNITED STATES PATENT OFFICE.

WILLIAM H. ROBERTSON, OF DAYTON, OHIO, ASSIGNOR TO THE NATIONAL CASH REGISTER COMPANY, OF DAYTON, OHIO, A CORPORATION OF MARYLAND.

CASH REGISTER.

Application filed August 16, 1926. Serial No. 129,452.

This invention relates to cash registers, and more particularly to the type shown and described in Letters Patent of the United States to Kettering and Chryst, No. 1,187,561, issued April 27, 1915, to which reference may be had for a complete description of the parts of the machine which do not relate directly to the present invention.

The object of this invention is to provide an improved means for controlling the printing of totals and subtotals.

Another object of this invention is to provide novel means to control the machine for adding, totalizing and sub-totalizing operations.

Another object of the present invention is to provide a novel totalizer engaging and disengaging controlling mechanism.

With this and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1 is a cross-section taken through the machine and shows the amount differential mechanism.

Fig. 2 is a right side elevation of the machine showing the total lever, the mechanism for releasing the machine, and the totalizer engaging and disengaging mechanism.

Fig. 3 is a detail view of the drawer latch mechanism.

Fig. 4 is a detail view of the total lever, together with its associated interlocking mechanisms.

Fig. 5 is a detail view of the type segment and some of the mechanism for adjusting the same.

Fig. 6 is a detail view of a part of the totalizer engaging and disengaging mechanism.

Fig. 7 is a detail view, on a reduced scale, of a portion of the transaction bank differential, together with a part of the mechanism for throwing out the totalizer engaging mechanism for charge and paid out transactions.

Fig. 8 is a detail view showing the manner in which the totalizer elements control the

totalizer actuator during total taking operations.

General description.

This machine is of the drawer operated type, that is, the type of machine in which the release of a cash drawer permits partial operation of the mechanism, and the restoring of the drawer by the operator completes the operation and stores up enough energy in a spring for the next operation of the machine. The machine may be provided with a bank of clerks' keys, a bank of transaction keys, and any number of banks of amount keys. The amount is set up on the amount keys, and a clerk's key and transaction key are depressed, after which the release key is depressed for releasing the cash drawer, thereby permitting the spring to operate the machine. The amount keys control differential mechanisms for adding the amounts into a totalizer and for setting up type segments and indicators. A printing mechanism, a portion of which is shown and described herein, is provided for recording the amounts set up on the type segments on the record strip which is retained in the machine.

A total lever is provided which has three positions of adjustment, one for adding, one for sub-total, and one for grand total operations. When the lever is set in the sub-total position, and the machine operated, the totalizer is cleared, the amount standing on the totalizer is set up on the type carriers and printed, and then re-entered into the totalizer. When the total lever is in its grand total position, the totalizer is cleared, the total is printed, but the totalizer is left standing at zero at the end of the operation.

Only so much of the mechanism is shown as is necessary to clearly illustrate the invention, a complete description of the machine being given in the above mentioned Kettering and Chryst Patent No. 1,187,061.

Detail description.

Each bank of amount keys 30 (Fig. 1), is adapted to differentially control a segment 31 for controlling the entry of an amount into a totalizer element 32. There is one segment 31 for each bank of keys 30. The amount keys are held in depressed position by means of detents 33, only a part of which is shown herein as they are fully illustrated

and described in the above mentioned Patent No. 1,137,061. The segments 31 are operated by means of springs 34, which are normally prevented from operating by a universal rod 35 carried by a pair of arms 36 (one only being shown). Each arm 36 is pivoted to a stud 37, one of which is mounted in the right side frame, and the other in the left side frame. The arms 36 are operated by means of a spring 38, when the drawer is released. However, the spring 38 is normally prevented from operating said arm 36, by means of a drawer latch 39 (Fig. 3) which engages a roller 40 carried in a bracket in the rear of a cash drawer 41. The latch is held in position by an arm 42 (Fig. 2) which at its lower end is provided with a shoulder 43 against which a roller 44 carried by an arm 45 rests. The arm 45 is secured to a shaft 55 to which is also secured an arm (not shown but having the same outline as the arm 45). This arm (not shown) has pivoted thereto one end of a link 46, the other end of which is pivoted to the drawer latch 39 (Fig. 3). A spring 47 (Fig. 2) connected to the link 46 and to the machine frame tends to move said link toward the rear of the machine thus holding the roller 44 against the shoulder 43. The arm 42 is permitted to move under the influence of a spring 48 when a release key 49 is depressed. The release key 49 is carried by a pair of arms 50 and 51, and is held in its outer position by a spring 52 which normally holds a lug 53 on the release key against a stud 54 carried in one of the frames of the machine. When the release key 49 is depressed the spring 48 causes the arm 42 to be rocked to disengage the shoulder 43 from the roller 44, thereby permitting the link 46 to move toward the rear of the machine and permit the latch 39 to rotate in a clockwise direction, thus freeing the cash drawer.

The cash drawer 41 is opened by a train of mechanism on each side of the machine. These mechanisms are substantially the same as those illustrated and described in the previously mentioned Kettering and Chryst Patent No. 1,137,061 and also a Kettering and Chryst Patent No. 1,011,966 issued on December 19, 1911. Therefore, in the present application only one of said trains of mechanism is shown, it being the one on the right hand side of the machine. This one train of mechanism will now be described.

Pivotedly mounted on a stud 67 (Fig. 2) on the side frame is a Y-shaped lever 60 adapted to be rocked clockwise under the influence of the spring 38 attached to the machine base and to a spring hook 57 hooked on a stud 58 on an arm 61 pivoted on a stud 59 on the machine frame. The lower end of said lever 60 is held in contact with the rear of the drawer 41 by the spring 38.

Pivoted to the arm 61 is one end of a link 62, the other end of which is pivoted to an arm 63 secured to a main operating shaft 64. Also secured to the shaft 64 is an arm 65 having connected thereto a link 66. This link is also connected to a stud 56 (Figs. 1 and 2) on the lever 60. This lever 60 is pivoted on a stud 67 carried by the machine frame, as above described.

From the above description it will be clear that when the release key 49 is depressed and the drawer latch 39 is released, as previously described, the spring 38 rocks a portion of both trains of mechanisms including the arms 61 and 63 and shaft 64. Said arms 61 and 63 and shaft 64 are rocked clockwise. This movement of the shaft 64 rocks other elements of both trains of mechanisms, including the arm 65, link 66 and lever 60 of each train, thus opening the drawer 41.

The remaining elements of each of said trains of mechanisms includes an arm 68 (Fig. 1) provided with a cam slot 69 into which projects a roller 70. The rollers 70 are carried by the previously described arms 36.

The clockwise movement of the shaft 64 causes the cam slots 69 to rock the arms 36 counter-clockwise thus lowering the universal rod 35, thereby permitting all of the segments 31 to be operated, by their springs 34, under control of the amount keys 30.

Totalizer.

The totalizer consists of a plurality of wheels 32 (one only being shown) each (Fig. 1) having secured thereto a pinion 75 mounted on a shaft 74 carried between a pair of arms 76 only one of which is shown. The totalizer pinions 75 are normally engaged with their actuating segments 77, but are adapted to be disengaged therefrom at the beginning of an operation of the machine, and before the segments 31 begin to move under control of the amount keys. Each actuating segment 77 is slidably mounted on a segment 31 for the purpose of permitting transfers to be made when any of the totalizer wheels move from nine to zero as shown and described in the above mentioned Kettering and Chryst Patent No. 1,137,061. Therefore, it is not thought necessary to describe the transfer mechanism herein. After the segment 77 has been positioned, the totalizer wheels are restored to their home position, thereby adding the amounts into the totalizer wheels.

The closing of the cash drawer 41 also restores both of the previously described trains of operating mechanisms to their normal positions. As the drawer is being closed its rear end contacts the levers 60 and rocks them counter-clockwise to normal position, thereby causing the links 66 and arms 65 to rock the shaft 64 counter-clock-

wise to normal position. This moves the arms 68 and 36 and raises the rod 35 thus restoring the segments 31 and actuating segments 77 to their home positions.

5 The movement of the shaft 64 also rocks the arms 63 and 61 counter-clockwise thus tensioning the spring 38 for a subsequent operation.

10 *Totalizer disengaging and engaging mechanism.*

As above mentioned, the totalizer pinions 75 are normally in engagement with its actuating segments 77. At the beginning of 15 the operation of the machine, a pitman 80 (Fig. 2), will cause the totalizer to be disengaged from the segments 77. The pitman is provided with a stud 81 which engages a notch in an arm 82 secured to a shaft 83, 20 to which the arms 76, which support the totalizer wheels, are also secured. The pitman 80 is first raised by means of a camming pawl 84 carried on the lever 60. When the drawer is released the camming pawl 84 25 engages a roller 85 on a lever 86 to which the pitman 80 is connected. The lever 86 is thus rocked in a clockwise direction, thus raising the pitman 80 and causing the totalizer pinions 75 to be disengaged from their 30 actuating segments 77. Just before the lower end of the lever 60 reaches its foremost position, during the clockwise movement thereof on its stud 67, the camming pawl 84 engages a roller 87 on the lever 86, 35 thereby rocking said lever 86 counter-clockwise thus causing the pitman 80 to be lowered to its normal position, and in this manner reengaging the totalizer pinion 75 with the segments 77. The segments 77 40 are adjusted during this clockwise movement of the lever 60, and restored for adding the amounts during the return or counter-clockwise movement of the lever 60.

45 *Totalizer throwout mechanism.*

During "charge" and "paid out" transactions it is desired to prevent amounts from being accumulated into the totalizer. As 50 previously stated the totalizer pinions 75 normally engage the segments 77 but immediately upon release of the drawer, the pawl 84 causes the pitman 80 to be raised, thus disengaging the pinions from the segments 77. In order to prevent the reengagement of the totalizer pinions 75 with the 55 actuating segments 77, a bell crank 95 (Fig. 2) is provided with a roller 96 which is adapted to engage a cam slot 97 in the pitman 80 for disengaging the stud 81 from the notch in the arm 82 before the pitman 80 is lowered by the camming pawl 84. The 60 movement of the bell crank 95 is controlled by the transaction bank differential controlling segment 31 (Fig. 7). This segment 65 31 for the transaction bank is provided with

two studs 98. The upper stud 98 is adapted to be moved into the path of a nose 99 of a pawl 100, when the machine is operated with the "charge" key depressed, and the other stud 98 is adapted to be moved into 70 the path of said nose 99, when the machine is operated with the "paid out" key depressed. This pawl 100 is pivoted on a stud 94 carried by an arm 101 secured to a shaft 102. These keys are not shown herein but 75 reference may be had to Fig. 1 of the above mentioned Patent No. 1,137,061 for an illustration thereof. If neither of these two keys is depressed, neither of the studs 98 is positioned in the path of the nose 99 of 80 the pawl 100 when the machine is operated, and the pawl 100 is moved bodily toward the rear of the machine with the arm 101 which is rocked clockwise by the shaft 102. The shaft 102 is rocked by means of a seg- 85 mental arm 103 (Figs. 1 and 7) secured to the cam shaft 64. The shaft 64 rocks the arm 103 clockwise. Said arm has a cam slot entered by a pin on one arm of a bell crank 104 pivoted on a shaft 153. A link 90 106 connects the opposite arm of the bell crank to an arm 105 fast on the shaft 102 to rock said shaft 102 and the arm 101 clockwise. This movement of the arm 101 is transmitted to a shaft 107 by means of 95 a link 108 connected to the pawl 100 and an arm 109 fast on the shaft 107. The bell crank 95 (Fig. 2) is also secured to the shaft 107 and therefore, when the arm 101 and pawl 100 (Fig. 7) are moved toward 100 the rear of the machine, the shaft 107 is rocked, thereby rocking the bell crank 95. If no stud 98 is in the path of the nose 99, the pawl 100 moves bodily with the arm 101, and said pawl does not turn on its pivot 105 stud 94 and, therefore, the shaft 107 is rocked only a short distance in a counter-clockwise direction. However, if one of the studs 98 is in the path of the nose 99 of 110 the pawl 100, as the arm 101 is rocked clockwise the nose 99 engages the stud 98, and as the arm 101 continues to rock the pawl 100 is rocked counter-clockwise on its pivot stud 94. This movement of the pawl 100, through the link 108 and arm 109 rocks the 115 shaft 107 counter-clockwise a greater distance. It will be remembered that the arm 101 moves the link 108 a certain distance but when the pawl 100 is rotated relatively to the arm 101, the link 108 receives from 120 said pawl an additional movement. This combined movement of the link 108, rocks the shaft 107 and bell crank 95 far enough to engage the roller 96 (Figs. 2 and 6) with the cam slot 97, thereby rocking the pitman 80 clockwise, with its lower end as the pivot point to disengage the stud 81 from the notch in the arm 82. The cam slot in the arm 103 is so timed that the bell crank 125 95 (Fig. 2) is not rocked to engage the roller 130

96 with the cam slot 97 until after the pitman 80 is raised to disengage the totalizer pinions 75 from their actuating segments 77.

Before the bell crank 95 is rocked far enough to rock the pitman 80 clockwise as just described, it is necessary to disengage a stud 183, carried by a pitman 182, from the portion 111 of the slot 184. The bell crank 95 has a slot 93 into which projects a pin 92 on the pitman 182. The counter-clockwise movement of the bell crank 95 rocks the stud 183 into the elbow of the slot 184. Now as the roller 96 enters the cam slot 97 the pitman 80 is free to be rocked clockwise and a portion 110 of the slot 184 engages the stud 183.

The bell crank 95 is also provided with a stud 115 (Fig. 2), which is adapted to engage the upper side of an arm 116, also secured to the shaft 83. This prevents a spring plunger 117, which normally holds the totalizer in its engaged position, from engaging the totalizer with its actuators when the stud 81 is disengaged from the notch of the arm 82.

The stud 81 is now in the enlarged aperture in the arm 82, and as the pawl 84 engages the roller 87 to lower the pitman 80, the arm 82 and shaft 83 are not rocked. Therefore, the pinions 75 remain disengaged from the segments 77 so that the amount of the charge or paid out transaction is not accumulated upon the totalizer wheels 32.

As the drawer 41 is closed, the drive shaft 64 is rotated counter-clockwise to normal position thus moving the arm 101, link 108 and bell crank 95 to normal. The pawl 84 rocks the lever 86 and raises the pitman 80 and the stud 81 again engages the notch in the arm 82 as the plunger 117 on the lever 60 restores the arms 116 and 82 to normal thus re-engaging the pinions 75 with their segments 77.

As the bell crank 95 completes its restoration it rocks the pitman 182 and moves the stud 183 into the portion 111 of the slot 184 thus holding the pitman 80 in normal position.

Amount key release mechanism.

Near the end of the operation of the machine, the detents 33 are lowered by a yoke 118 (Figs. 1 and 6), for releasing all of the amount keys. This yoke is rocked by a spring pressed pawl 119 (Fig. 2), pivoted on the arm 60, adapted to engage a roller 120 (Figs. 2 and 6), near the end of the operation of the machine, to rock a lever 121, thereby moving a link 122 toward the rear of the machine. The link 122 is held in engagement with a stud 123 on the yoke 118 by a stud 124 on the link 122 which enters a slot 125 in an arm 126. The arm 126 is normally held in the position shown in a manner to be hereinafter described.

When the lever 60 is restored to normal position the pawl 119 restores the lever 121 and yoke 118 to their normal positions.

Full stroke mechanism.

A full stroke mechanism of the usual type is provided which compels a complete operation of the machine. This mechanism consists of a spring-pressed pawl 130 (Fig. 2) pivoted on the lever 60, and cooperates with a bar 131 carried by the right side frame of the machine. The bar 131 is provided with a series of notches 132 with which the pawl 130 cooperates to prevent return of the lever 60 before the pawl has passed the last notch, whereupon a spring 133 causes the pawl to assume its normal position and during the return stroke of the lever 60, the pawl co-operates with the notches 132 to prevent forward movement of the lever 60 until after the lever has completed its rearward movement.

An arm 137 cooperates with a Z-bar 134, to prevent release of the drawer until after the pawl 130 comes into contact with the first notch 132. This arm 137 is pivoted on the bar 131 and is provided with an opening 135 into which projects a stud 136 carried by the beforementioned lever 86. As the lever 86 is rocked by the camming pawl 84 the stud 136 engages the inclined wall of the opening 135, thereby lifting the arm 137 out of the path of the Z-bar 134, thereby permitting the drawer to open.

Printing mechanism.

A printing segment 145 (Fig. 5) is provided for each totalizer wheel 32. These segments are adjusted under control of the segments 31. Pivoted to each of the segments 31 is a beam 146 (Fig. 1) connected to an arm 147 by a link 148. The arms 147 are each secured to a shaft 149 to each of which is also secured an arm 150 (Fig. 5), connected to its corresponding type segment 145 by means of a link 151.

When any one of the segments 31 (Fig. 1) is positioned under control of the amount keys 30 as before described, the forward end of the beam 146 is positioned accordingly. After the forward end is positioned an aliner (not shown) is rocked into engagement with the segment 31 to lock it in its adjusted position. After the segment is so locked, an arm 152 secured to a shaft 153 is rocked by the segmental arm 103 to cause one of the cam surfaces 154 of the arm 152 to engage a roller 155 carried by the beam 146, thereby positioning the rear end of the beam according to the position of its forward end. This movement is transmitted to the type segment 145, and in this manner adjusting it according to the position of the segment 31 as controlled by the amount key.

A platen 156, over which the record ma-

terial is fed, is rocked into engagement with the type segments 145, thereby causing an impression to be made. This impression mechanism is not shown or described herein but reference may be had to the above mentioned Patent No. 1,137,061.

After the impression is made the arm 103 restores the arm 152 to normal position and as the segment 31 is restored to normal, the 10 left end of the beam 146, as viewed in Fig. 1, is likewise restored to normal position. The right end of the beam 146 remains in the position to which it was adjusted thus permitting the type segments to remain in adjusted position until a subsequent operation.

Indicating mechanism.

The beam 146 also adjusts indicators 160 (Fig. 1) by means of a link 161 which is 20 connected to the link 148 at one end, and at the other end is connected to a segment 162. The segment 162 adjusts the indicator by means of a pinion 163 according to the adjustment of the beam 146. Since the right 25 ends of the beams 146 remain in adjusted position until a subsequent operation, as explained above, the indicators 160 also remain in their adjusted positions until a subsequent operation.

30 *Total taking mechanism.*

The machine is adapted to print grand totals and sub-totals of the amount standing on the totalizer. The mechanism for 35 taking totals is controlled by a lever 170 (Figs. 2 and 4), which has three positions of adjustment, namely, adding, sub-total and grand total. In machines of this type the tripped transfer devices are restored during 40 the next succeeding cycle of operation, and therefore it is always necessary to perform one idle operation before a total is printed. During this idle operation the indicators are also restored to zero. An interlock is pro- 45 vided which makes it impossible to move the total lever 170 out of its adding position until after all of the indicators have been set to zero thus compelling the operator to make said idle operation.

50 This total making mechanism consists of an arm 171 (Fig. 4), fast on a shaft 169 and provided with a roller which is held in contact with the inner surface of the segment 162 by means of a spring 172. When any one 55 of the indicators is out of the zero position, an arm 173 also fast on the shaft 169 and having a flange 174 is held in the path of a flange 175 on the total lever. However, when all of the indicators are moved to zero, 60 the roller on the arm 171 is moved into a cut-away portion 176 of the segment 162, thereby lowering the flange 174 out of the path of the flange 175 thus permitting the operator to adjust the total lever 170.

65 The total lever 170 is provided with a

knob 177 which projects through a slot in the cabinet (not shown) of the machine and is provided for adjusting the total lever. A spring operated alining pawl 178 cooperates with notches 179 for holding the total lever 70 in the position to which it is adjusted.

When the total lever is moved to its first position out of adding position the mechanism is set for a sub-total operation. When moving the total lever, a cam slot 180 therein, 75 (Fig. 2), cooperates with a stud 181, to shift a pitman 182 toward the right (Fig. 2) and by means of a stud 183 projecting into the slot 184 in the pitman 80, disengages the stud 81 from the notch in the arm 82 thus moving the pitman 80 into a neutral position. Then, upon operation of the machine, when the pitman 80 is raised, the totalizer pinions 85 20 are not disengaged from the actuating segments 77 and therefore the totalizer controls the positioning of the segments 77 and 31 in a manner to be presently described.

During the lowering or return movement of the pitman 80 the stud 81 remains disengaged from the notch in the arm 82, and therefore, during the entire operation of the machine, the totalizer pinions 75 are in engagement with the segments 77.

During all total taking operations, the totalizer pinions 75 controls the movement of 90 the segments 31. Each pinion 75 is provided with a pin 188 (Fig. 8), which engages a shoulder on an arm 190 to stop the rotation of the pinion 75 when the totalizer wheel 32 reaches the zero position, thereby preventing further rotation of its associated segment 31 in a clockwise direction, thus stopping the type and indicator segments in positions commensurate with the amount which was standing on the totalizer wheels. When the segments 31 are returned to their 100 home position, during sub-total operations, this amount is again added on the totalizer wheels.

The type segments 145 and the indicators 110 160 are adjusted to set up and indicate the amount standing on the totalizer wheels in the same manner as during adding operations, and therefore no further description thereof will be necessary.

When the total lever 170 is moved to its second position out of adding position, the pitman 182 of Fig. 2 is moved far enough to the right to disengage the stud 81 from the notch in the arm 82, and to engage a stud 191 on the pitman 80 with a notch 192 in the arm 116. During this latter movement of the pitman 80 by the pitman 182, the stud 191 engages the surface 193 and the pitman 80 is thereby cammed upwardly until the stud 191 is engaged with the notch 192. This upward movement of the pitman 80 rocks the lever 86 clockwise far enough to move the roller 85 out of the path of the camming pawl 84. Upon subsequent opera- 120 125 130

tion of the machine, the camming pawl 84 has no effect upon the lever 86, until near the end of its forward movement, when it engages the roller 87, thereby lowering the pitman 80 and disengaging the totalizer pinions 75 from its actuating segments 77. With the totalizer thus disengaged, and operation of the machine completed, the segments 31 and 77 are returned to their home 10 positions, and the totalizer wheels are left standing at zero.

Key release throughout mechanism.

During total taking operations a mechanism (not shown herein) is provided for locking the detents 33 against movement in order to prevent depression of the amount keys. For this reason it is necessary to prevent movement of the key release mechanism during total taking operations. It will be remembered that the keys are released by rocking the yoke 118 by the link 122 (Fig. 6). When the pitman 182 is moved toward the rear of the machine, upon adjustment of the 25 total lever 170 (Fig. 5), a stud 194 on the pitman 182 cooperates with a cam slot 195 in the arm 126, and cams said arm 126 in a clockwise direction, thereby disengaging the link 122 from the stud 123, and in this manner preventing operation of the yoke 118.

Interlock.

An interlock is provided to prevent adjustment of the total lever 170 after the machine 30 has begun to operate, and to prevent depression of the release key 49 when the total lever is not exactly in one of its three positions of adjustment. This means includes an arm 200 fast to the arm 50, and having a stud 201 35 adapted to engage any one of the slots 202 in the total lever 170 when the total lever is in any of its three positions. If the total lever 170 is not exactly in any of the three 40 positions, upon an attempted depression of the release key 49, the stud 201 engages the periphery of the total lever 170, thereby preventing complete depression of the release key 49. When, however, the total lever 170 is exactly in one of its positions of 45 adjustment and the release key 49 is depressed, the stud 201 then enters one of the slots 202, and it is then impossible to adjust the total lever to any of its other positions until after the machine is operated and 50 returned home, and the release key returned to its home position.

A device has been provided for preventing adjustment of the total lever 170 to any position other than adding position, unless the 55 totalizer lid 203 is unlocked and opened. This lid has a projection 204 in the path of an arm 205 secured to a shaft 206 actuated by the arm 126. Before the total lever can be moved, the projection 204 must be moved 60 out of the path of the arm 205 so that the

shaft 206 is free to be rotated by the arm 126. This can only be accomplished by first unlocking and opening the lid 203. The object of this arrangement is to prevent anyone, except the proprietor, from taking totals 75 off the machine.

While the form of mechanism herein shown and described is admirably adapted to fulfill the object stated, it is to be understood that it is not intended to confine the invention to the one form of embodiment herein disclosed, for it is susceptible of embodiment in various forms all coming within the scope of the claims which follow.

What is claimed is:

1. In a machine of the class described, the combination of a totalizer, actuators therefor, a member for disengaging and engaging the totalizer with the actuators, a pitman for moving the member into an ineffective position for sub-total operations and into an effective position for grand total operations, and a lever for controlling said pitman.

2. In a machine of the class described, the combination of a totalizer, actuators therefor, a member for disengaging and engaging the totalizer with the actuators, and a lever having a cam slot adapted to control the position of the member whereby said member is moved into an ineffective position during sub-total operations and into an effective position during grand-total operations.

3. In a machine of the class described, the combination of a totalizer, actuators therefor, a member for disengaging and engaging the totalizer with the actuators, a lever having a cam slot adapted to control the position of the member whereby said member is moved into an ineffective position during sub-total operations and into an effective position during grand-total operations, and a pitman for transmitting movement from the lever to the member as determined by said cam slot.

4. In a machine of the class described, the combination of a totalizer, actuators therefor, means for engaging and disengaging the totalizer with the actuators, a pitman for determining the position of said means, and a lever for shifting said pitman to an ineffective position and for moving said means to an ineffective position.

5. In a machine of the class described, the combination of a totalizer, actuators therefor, means for engaging and disengaging the totalizer with the actuators, a pitman for determining the position of said means, a lever for controlling the effectiveness of said pitman, means for controlling the movement of the lever whereby the pitman is moved to an ineffective position after the totalizer has been disengaged, and a projection on said lever adapted to shift said first mentioned 130

means to an ineffective position thereby preventing re-engagement of the totalizer with the actuators.

6. In a machine of the class described, the combination of a totalizer, actuators therefor, means for engaging and disengaging the totalizer with the actuators, a pitman, a stud on said pitman adapted to project into a slot in said means, a lever adapted to maintain the stud in engagement with said slot, a projection on said means having a cam slot, a stud on said lever adapted to engage the cam slot, and means for controlling the movement of said lever whereby the first mentioned stud is disengaged from the slot, thereby permitting the second mentioned stud to shift the means to ineffective position upon the engagement of the second mentioned stud with the cam slot.

20 7. In a machine of the class described, the combination of a totalizer, actuators therefor, a device for disengaging and engaging the totalizer with the actuators, means for controlling said device for adding and total taking operations, a differential mechanism, and means controlled by said differential mechanism for disconnecting said device from said means and for positioning said device whereby the totalizer will not be engaged with the actuators.

25 8. In a machine of the class described, the combination of a totalizer, actuators therefor, a pitman for disengaging and engaging the totalizer with the actuators during adding and total taking operations, a lever operatively connected with said pitman for controlling its position, a differential mechanism, and means controlled by the differential mechanism for disconnecting the pitman

from said lever and for shifting said pitman 40 into a position whereby the totalizer will not be engaged with its actuators during certain adding operations.

9. In a machine of the class described, the combination of a totalizer, actuators therefor, a pitman for disengaging and engaging the totalizer with the actuators, a lever for controlling the engagement of the totalizer during adding and total taking operations, a transaction differential mechanism, a bell 50 crank controlled by said differential, connections between said bell crank and said lever for controlling the pitman, said connections being held in operative relation with said pitman during certain adding operations by said bell crank and adapted to be rocked out of operative relation with said pitman by said bell crank during other adding operations, and means on said bell crank for rocking said pitman into a position in 55 which the totalizer will not be engaged with the actuators during other adding operations thereby preventing the addition of the amounts.

10. In a machine of the class described, 65 the combination of a totalizer actuator, a totalizer normally in engagement therewith, a member normally in an effective position to disengage the totalizer from the actuator, means connected to said member and adapted to move said member into an ineffective position for subtotal operations and into a second effective position for grand total operations, and a lever having a single slot to move said member into its various positions. 70 75
In testimony whereof I affix my signature.

WILLIAM H. ROBERTSON.
